(57) **CLAIM**

The ornamental design for a cartridge filling device, as shown and described.

DESCRIPTION

FIG. 1 is a perspective view of a cartridge filling device, according to one preferred embodiment of the invention; FIG. 2 is a right side view of the cartridge filling device shown in FIG. 1;

FIG. 3 is a back view of the cartridge filling device shown in FIG. 1;

FIG. 4 is a front view of the cartridge filling device shown in FIG. 1;

FIG. 5 is a left side view of the cartridge filling device shown in FIG. 1;

FIG. 6 is a bottom view of the cartridge filling device shown in FIG. 1; and,

FIG. 7 is a top view of the cartridge filling device shown in FIG. 1.

The broken lines represent unclaimed portions of the cartridge filling device and form no part of the claimed design.
